(57) **CLAIM**

The ornamental design for a circle burner attachment for a plasma torch, as shown and described.

DESCRIPTION

FIG. 1 is an isometric view of the circle burner attachment for a plasma torch of the present invention;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a left side elevation view thereof, the right side elevation view being a mirror image thereof.
